N. M. GOODLETT

APPARATUS FOR OPERATING ON PAPER AND OTHER FABRICS

Filed April 17, 1920

Nicholas M. Goodlett
Inventor

UNITED STATES PATENT OFFICE.

NICHOLAS M. GOODLETT, OF NEW YORK, N. Y., ASSIGNOR TO ARKELL SAFETY BAG COMPANY, OF NEW YORK, N. Y., A CORPORATION OF NEW YORK.

APPARATUS FOR OPERATING ON PAPER AND OTHER FABRICS.

Application filed April 17, 1920. Serial No. 374,636.

This invention relates to a new apparatus for operating on paper.

One object of the invention is the provision of improved means in the production 5 of paper that shall be stretchable in two directions, that is, longitudinally and transversely. Another object of the invention is the production of such paper by forming crinkles crosswise of the paper after 10 it has been corrugated lengthwise. Another object is to form in the paper such longitudinal corrugations and cross crinkles during the forward travel of the paper in the web. Another object is to operate on the 15 paper with no more moisture in it than is properly required to form the crinkles and thus reduce the cost of subsequently drying the paper. In some cases, the paper may be operated upon without the previous 20 addition of moisture. Other objects of the invention will appear from the following description.

The invention consists of the structure and arrangement and in the steps of operation 25 hereinafter set forth.

In the accompanying drawings, forming part of this specification, and in which like reference numerals designate corresponding parts, the apparatus is shown in one of its 30 various embodiments.

Fig. 1 is a central sectional elevation of a suction crinkling cylinder and associated parts.

Fig. 2 is a view of said cylinder, partly 35 in section, with its associated doctor, looking from above.

Fig. 3 is a diagrammatic view of the series of corrugating rolls shown in Fig. 1.

Referring to the particular structure, as 40 shown in the drawings, 1 is a perforated suction cylinder mounted on a fixed tubular shaft 2 which is open to the interior by the openings 3. The open end of the shaft 2 connects with a pipe 4 leading to a suitable suction pump 5 which may be driven by an electric motor 6. The pipe 4 is provided with a relief valve 7 which may be operated to regulate the suction in the pipe 4. 8 is a suction box movably mounted on 45 the shaft 2 and communicating therewith

through the openings 3. It is held in place on the shaft 2 by set screws 9 and 10. These set screws provide for the circumferential adjustment of the suction box 8 so that the area of pressure on the paper may be adjusted relative to the doctor 12. As thus described, the suction cylinder and associated parts have substantially the same construction and operation as that shown and described in my former application Serial 60 No. 267,430, filed December 19, 1918.

The crinkling cylinder 1 is provided with a series of circumferential grooves 11 which give the cylinder a corrugated surface. 12 is the doctor or crinkle-forming abutment. 65 Its inner or operating edge is provided with teeth or serrations 13 which fit into the grooves 11 of the cylinder. Cooperating with the cylinder 1 is a set of corrugating rolls 14, 15, 16, 17, 18 and 19. The paper on the cylinder passes underneath these rolls in the order named. Roll 14 is provided with a single boss 20 arranged to enter the central groove of the cylinder 1. Roll 15 is provided with a middle boss in alignment with the boss 20 and with two additional bosses all similar to boss 20 and arranged to enter the grooves on either side of that in which boss 20 operates. The remaining corrugating rolls are similarly provided with bosses, each roll having bosses in alignment with those on the preceding roll and two bosses in addition, the last roll 19 having as many bosses as there are grooves in the cylinder 1. These corrugating rolls act to press the paper down into the grooves 11 and they act upon the paper progressively from the middle outward.

21 is the web of paper passing through the apparatus. After it meets the doctor 12, 90 it emerges as the web 22 provided with crinkles across its surface and with corrugations longitudinal thereof. The web 21, before entering the apparatus, may be in a flat smooth state. In this case the corrugating rolls 14 and 19 progressively press it into the grooves 11 of cylinder 1 and thereby form corrugations in it. The suction box 8 causes the paper to be held on the cylinder and in the grooves thereof by 95 100

air pressure immediately in advance of and at the doctor 12. This pressure on the paper or holding of the paper down on the cylinder resists the stripping action of the doctor. It also enables the paper to be suitably crinkled in a drier state than would be otherwise possible. If desired, the web 21, before being fed to the cylinder 1, may previously have been provided with longitudinal corrugations. In this case, the corrugating rolls 14 to 19 may act merely to further set the corrugations so previously formed or they may act to increase the depth and sharpness of such corrugations. Furthermore, in cases where the paper 21 has been previously corrugated, or in cases where it is not desired to form corrugations in the paper, the corrugating rolls 14 to 19, as elements cooperating directly with the crinkling cylinder 1, may be dispensed with. Rolls 14 to 19 may be made of any suitable material, yielding or otherwise. They may be friction-driven from cylinder 1 or they may be driven from any other source of power.

23 is a tank containing hot water through which the paper may pass beneath submerging rolls 24 if it is desired to wet the paper before it passes on to the cylinder 1. Other means for moistening the paper may be used. 25 is a guide roll for the paper on its way to the cylinder 1.

While it is preferred that the supporting surface for the paper in cooperation with the corrugating rolls and in cooperation with the doctor or crinkle-forming abutment be in the form of a cylinder, the invention is not restricted to such form of supporting surface. And while it is preferred to use fluid pressure, and particularly air pressure provided by a suction box, to hold the paper on the cylinder and in the grooves thereof, and particularly immediately in advance of or at the doctor, the invention contemplates any means for thus holding the paper or for applying pressure to the paper in cooperation with a grooved supporting surface and a doctor or other crinkle-forming means. By crinkling paper that has been previously corrugated in accordance with this invention, the crinkles extend across the paper in zig-zag lines and therefore, of themselves, provide for a certain transverse stretchability of the paper. Such transverse stretchability is increased by the longitudinal corrugations formed in the paper.

It will be seen that the present invention contemplates an extension or new application of the invention set forth in my former application Serial No. 267,430, filed December 19, 1918.

What I claim is:

1. In an apparatus for operating on paper, the combination of a supporting surface for the paper having grooves therein parallel

with the direction of travel of the paper and a crinkle-forming abutment having serrations fitting into said grooves, and means for applying fluid pressure to the paper immediately in advance of the abutment. 70

2. In an apparatus for operating on paper, the combination of a supporting surface for the paper having grooves therein parallel with the direction of travel of the paper and a crinkle-forming abutment having serrations fitting into said grooves, and fluid pressure means for holding the paper down on said surface immediately in advance of the abutment. 75

3. In an apparatus for operating on paper, the combination of a supporting surface for the paper having grooves therein parallel with the direction of travel of the paper and a crinkle-forming abutment having serrations fitting into said grooves, and fluid pressure means operative immediately in advance of the abutment to limit the stripping action thereof. 80

4. In an apparatus for operating on paper, the combination of a supporting surface for the paper having grooves therein parallel with the direction of travel of the paper and a crinkle-forming abutment having serrations fitting into said grooves, and means for causing the paper to adhere to said surface by fluid pressure. 90

5. In an apparatus for operating on paper, the combination of a supporting surface for the paper having grooves therein parallel with the direction of travel of the paper and a crinkle-forming abutment having serrations fitting into said grooves, and means for causing the paper to adhere to said surface by fluid pressure, the area of pressure and said abutment being relatively adjustable to 100 and from each other. 105

6. In an apparatus for operating on paper, a rotating cylinder for the paper having transverse grooves therein and a crinkle-forming abutment having serrations fitting 110 into said grooves, in combination with means for holding the paper down on said cylinder by fluid pressure immediately in advance of the abutment.

7. In an apparatus for operating on paper, a rotating cylinder for the paper having transverse grooves therein and a crinkle-forming abutment having serrations fitting 115 into said grooves, in combination with means for causing the paper to adhere to said cylinder by fluid pressure. 120

8. In an apparatus for operating on paper, a rotating cylinder for the paper having transverse grooves therein and a crinkle-forming abutment having serrations fitting 125 into said grooves, in combination with means for causing the paper to adhere to said cylinder by fluid pressure, the area of pressure and said abutment being relatively adjustable to and from each other. 130

9. In an apparatus for operating on paper, the combination of a supporting surface for the paper having grooves therein parallel with the direction of travel of the paper, 5 means for pressing the paper into said grooves, means to crinkle the paper, and means for causing the paper to adhere to said surface by fluid pressure immediately in advance of said means to crinkle.
10. In an apparatus for operating on paper, the combination of a supporting surface for the paper having grooves therein parallel with the direction of travel of the paper, means for pressing the paper into 15 said grooves, a crinkle-forming abutment having serrations fitting into said grooves, and means for causing the paper to adhere to said surface by fluid pressure immediately in advance of said abutment.
11. In an apparatus for operating on paper, the combination of a supporting surface for the paper having grooves therein parallel with the direction of travel of the paper and a crinkle-forming abutment having 25 serrations fitting into said grooves, means for causing the paper to adhere to said surface by fluid pressure, and means for forming corrugations in the paper in advance of said abutment.
12. In an apparatus for operating on paper, a rotating cylinder for the paper having transverse grooves therein and a crinkle-forming abutment having serrations fitting into said grooves, in combination with means 35 for holding the paper down on said cylinder by fluid pressure immediately in advance of the abutment, and means for forming corrugations in the paper in advance of said abutment.
13. In an apparatus for operating on paper, a rotating cylinder for the paper having transverse grooves therein and a crinkle-forming abutment having serrations fitting into said grooves, in combination with means 45 for causing the paper to adhere to said cylinder by fluid pressure, and means for forming corrugations in the paper in advance of said abutment.
14. In an apparatus for operating on paper, the combination of a supporting surface for the paper having grooves therein parallel with the direction of travel of the paper and a crinkle-forming abutment having serrations fitting into said grooves, and means for progressively forming corrugations in the paper in advance of said abutment. 50
15. In an apparatus for operating on paper, the combination of a supporting surface for the paper having grooves therein parallel with the direction of travel of the paper and a crinkle-forming abutment having serrations fitting into said grooves, and means for forming corrugations in the paper in advance of said abutment, said means 55
- comprising a series of corrugating rolls arranged to act progressively.
16. In an apparatus for operating on paper, the combination of a supporting surface for the paper having grooves therein 70 parallel with the direction of travel of the paper and a crinkle-forming abutment having serrations fitting into said grooves, means for applying pressure to the paper immediately in advance of the abutment, and means for progressively forming corrugations in the paper in advance of said abutment.
17. In an apparatus for operating on paper, the combination of a supporting surface for the paper having grooves therein 75 parallel with the direction of travel of the paper and a crinkle-forming abutment having serrations fitting into said grooves, means for applying pressure to the paper immediately in advance of the abutment, and means for forming corrugations in the paper in advance of said abutment, said means comprising a series of corrugating rolls arranged to act progressively. 80
18. In an apparatus for operating on paper, the combination of a supporting surface for the paper having grooves therein parallel with the direction of travel of the paper and a crinkle-forming abutment having serrations fitting into said grooves, means for holding the paper down on said surface immediately in advance of the abutment, and means for progressively forming corrugations in the paper in advance of said 90 abutment. 95
19. In an apparatus for operating on paper, the combination of a supporting surface for the paper having grooves therein parallel with the direction of travel of the paper and a crinkle-forming abutment having serrations fitting into said grooves, means for holding the paper down on said surface immediately in advance of the abutment, and means for forming corrugations 100 in the paper in advance of said abutment, said means comprising a series of corrugating rolls arranged to act progressively. 105
20. In an apparatus for operating on paper, the combination of a supporting surface for the paper having grooves therein parallel with the direction of travel of the paper and a crinkle-forming abutment having serrations fitting into said grooves, means for causing the paper to adhere to 110 said surface by fluid pressure, and means for progressively forming corrugations in the paper in advance of said abutment. 115
21. In an apparatus for operating on paper, the combination of a supporting surface for the paper having grooves therein parallel with the direction of travel of the paper and a crinkle-forming abutment having serrations fitting into said grooves, means for causing the paper to adhere to 120 said surface by fluid pressure, and means for progressively forming corrugations in the paper in advance of said abutment. 125
- 130

- said surface by fluid pressure, and means for forming corrugations in the paper in advance of said abutment, said means comprising a series of corrugating rolls arranged to act progressively.
22. In an apparatus for operating on paper, a rotating cylinder for the paper having transverse grooves therein and a crinkle-forming abutment having serrations fitting into said grooves, and means for progressively forming corrugations in the paper in advance of said abutment.
23. In an apparatus for operating on paper, a rotating cylinder for the paper having transverse grooves therein and a crinkle-forming abutment having serrations fitting into said grooves, and means for forming corrugations in the paper in advance of said abutment, said means comprising a series of corrugating rolls arranged to act progressively.
24. In an apparatus for operating on paper, a rotating cylinder for the paper having transverse grooves therein and a crinkle-forming abutment having serrations fitting into said grooves, in combination with means for holding the paper down on said cylinder immediately in advance of the abutment, and means for progressively forming corrugations in the paper in advance of said abutment.
25. In an apparatus for operating on paper, a rotating cylinder for the paper having transverse grooves therein and a crinkle-forming abutment having serrations fitting into said grooves, in combination with means for holding the paper down on said cylinder immediately in advance of the abutment, and means for forming corrugations in the paper in advance of said abutment, said means comprising a series of corrugating rolls arranged to act progressively.
26. In an apparatus for operating on paper, a rotating cylinder for the paper having transverse grooves therein and a crinkle-forming abutment having serrations fitting into said grooves, in combination with means for causing the paper to adhere to said cylinder by fluid pressure, and means for progressively forming corrugations in the paper in advance of said abutment.
27. In an apparatus for operating on paper, a rotating cylinder for the paper having transverse grooves therein and a crinkle-forming abutment having serrations fitting into said grooves, in combination with means for causing the paper to adhere to said cylinder by fluid pressure, and means for forming corrugations in the paper in advance of said abutment, said means comprising a series of corrugating rolls arranged to act progressively.
28. In an apparatus for operating on paper, a rotating perforated suction cylinder for the paper having transverse grooves
- therein and a crinkle-forming abutment having serrations fitting into said grooves.
29. In an apparatus for operating on paper, a rotating perforated suction cylinder for the paper having transverse grooves therein and a crinkle-forming abutment having serrations fitting into said grooves, and means for forming corrugations in the paper in advance of said abutment.
30. In an apparatus for operating on paper, a rotating perforated suction cylinder for the paper having transverse grooves therein and a crinkle-forming abutment having serrations fitting into said grooves, and means for progressively forming corrugations in the paper in advance of said abutment.
31. In an apparatus for operating on paper, a rotating perforated suction cylinder for the paper having transverse grooves therein and a crinkle-forming abutment having serrations fitting into said grooves, and means for forming corrugations in the paper in advance of said abutment, said means comprising a series of corrugating rolls arranged to act progressively.
32. In an apparatus for operating on paper, the combination of a supporting surface for the paper having grooves therein parallel with the direction of travel of the paper, and means cooperative with said grooves for forming corrugations in the paper, said means comprising a series of corrugating rolls arranged to act progressively.
33. In an apparatus for operating on paper, a rotating cylinder for the paper having transverse grooves therein, and means cooperative with said grooves for progressively pressing the paper into said grooves.
34. In an apparatus for operating on paper, a rotating cylinder for the paper having transverse grooves therein, and means cooperative with said grooves for forming the corrugations in the paper, said means comprising a series of corrugating rolls arranged to act progressively.
35. In an apparatus for making crinkled paper, a rotating perforated cylinder for the paper having transverse grooves therein, and means for exhausting the air from between the paper and the surface of the cylinder.
36. In an apparatus for making crinkled paper, a rotating perforated cylinder for the paper having transverse grooves therein, and a suction box inside said cylinder for exhausting the air from between the paper and the surface of the cylinder.
37. In an apparatus for making crinkled paper, a rotating perforated cylinder for the paper having transverse grooves therein, a crinkle forming abutment, and means for exhausting the air from between the paper and the surface of the cylinder.
38. In an apparatus for making crinkled paper, a rotating perforated cylinder for the

paper having transverse grooves therein, a serrated crinkle-forming abutment, and a suction box inside said cylinder for exhausting the air from between the paper and the 5 surface of the cylinder.

39. In an apparatus for making crinkled paper, a rotating perforated cylinder for the

paper having transverse grooves therein, and means for holding the paper down on said cylinder by fluid pressure. 10

This specification signed this sixteenth day of April, 1920.

NICHOLAS M. GOODLETT.
